UNITED STATES PATENT OFFICE

LESLIE W. CLAYBOURN, OF MILWAUKEE, WISCONSIN

MEANS FOR REGISTERING PRINTING PLATES

Application filed May 14, 1928. Serial No. 277,571.

My invention relates to registering means in the printing art, is described in connection with registering printing plates, is applicable where it is desired to print various plates in a definite relation to each other, and is especially useful in multi-color printing, wherein successive printings in different colors are imposed one on the other and it is desirous to have the printing lines for the various colors register one with the other.

It is the object of my invention to cause registry between plates without defacing the printing portions of the plates or imposing marks on said printing portions; and, further, to provide means whereby printing plates are located in predetermined position and provided with marks similarly related on complementary plates.

It is the object of my invention, further, to provide novel means whereby to position a printing plate on a bed; further, to provide novel means whereby to mark the printing plate; further, to provide a novel transparent sheet for receiving an impression from a printing plate and whereby to position complementary printing plates with relation to said impression; further, to provide such positioned printing plate with register marks; further, to provide a novel base having register marks with which the register marks on the printing plate are arranged to register for locating the printing plate in registry position on the base; further, to provide novel means for co-registering neighboring bases; and, further, to provide novel means for fixing the registry relation between bases.

The invention will be further readily understood from the following description and claims, and from the drawings, in which latter:

Fig. 1 is a plan view, partly broken away, showing my improved means.

Fig. 2 is a cross-section of the same, taken on the irregular line 2-2 of Fig. 1.

Fig. 3 is a side elevation of my improved registering means, partly broken away, and partly in vertical section on the line 3-3 of Fig. 1.

Fig. 4 is a plan view detail of one of the

hinging means for the hinged frame-members.

Fig. 5 is a detail in vertical section, taken on the line 5-5 of Fig. 9, showing the marking means of my improved device.

Fig. 6 is a detail cross-section of the securing means for the celluloid plate, taken on the line 6-6 of Fig. 1.

Fig. 7 is a side elevation of my improved device, showing the pivoted frame-members in different raised positions and partly broken away.

Fig. 8 is a rear elevation of my improved device, partly broken away, and partly in section on the line 8-8 of Fig. 3, showing the pivoted frame in elevated position for operation in connection with type-high printing plates.

Fig. 9 is a plan view of my improved device, with the pivoted frame raised, and showing the marking device in position for use.

Fig. 10 is a detail view of the marking means, shown in vertical section on the line 10-10 of Fig. 5.

Fig. 11 is a plan view detail of the connecting means between the frame-members.

Fig. 12 is a cross-section of the same, taken on the line 12-12 of Fig. 11.

Fig. 13 is a plan view showing positioned printing plates and bases in registered relations.

Fig. 14 is a cross-section of the same, taken on the line 14-14 of Fig. 13, partly broken away.

Fig. 15 is a longitudinal section taken in the plane of the line 15-15 of Fig. 14, and partly broken away.

Fig. 16 is a cross-section of a detail of the same, taken in the plane of the line 16-16 of Fig. 14; and,

Fig. 17 is a perspective view of a marking blade used for type-high plates.

A suitable bed 21 is provided with a supporting surface 22 for a printing plate, exemplified at 23, (Figs. 1, 2 and 9) or the supporting surface may support any other objects to be registered, for instance, a type-high printing block 24, exemplified in Fig. 8, all of which objects are for the purposes

of this invention included in the term plate or printing plate.

Plate positioning parts 26, shown as plate-hooks, are arranged to slide in grooves 27 in the bed, and are exemplified as having threaded connection with screws 28, respectively journaled in bearings 29, 30, fixed to the bed, and provided with operating handles 31, shown as knurled knobs, for rotating the screws and thereby moving the plate-hooks lengthwise of the grooves for locating the printing plate (Figs. 1 and 2). The respective screws are held endwise in their bearings. A number of these positioning parts are provided, two of the same being shown at each side of the printing plate and one at each end of the printing plate. (See Fig. 9.)

The bed is provided with slots 35, 36, 37, 20 38. Opposite walls of the slots 35, 36, are in line with each other, for forming a centering line 39, and opposite walls of the slots 37, 38, are in line with each other, for forming a centering line 40 (Fig. 9). The centering lines are perpendicular to each other and are imposed upon the supporting surface for providing centering lines for the printing plate which are preferably at substantially right angles to each other.

30 A marking tool is arranged to slide in these slots. The marking tool is exemplified as comprising a slide 41, provided with a tongue 42 received in the respective slots in the bed, and having a marking part 43 thereon (Figs. 5, 9 and 10). The marking part is shown as a blade received in a slot 44 in the slide, and clamped in the slot by a flange 45 of a screw 46, threaded into the threaded hole 47 in the slide. A handle 48 is provided with a socket 49 received over the outer shank 50 of the screw (Fig. 10), and arranged to be held to the clamping screw by means of a pin 51 received through the hub 52 of the handle and a hole in the upper extension of the screw, the parts being assembled preferably so that the handle extends lengthwise of the slide when the marking part is clamped, for convenience in manipulation.

The marking part is shown provided with 50 a beveled marking edge 53, the bevel of which corresponds to the bevel of the beveled edge 54 of the printing plate 23 exemplified (Fig. 5). The marking edge of the tool preferably moves in registry with the centering lines 39, 40, on the bed, so that the registering marks 55, 56, on the plate will be coincident with the centering lines on the bed (Figs. 9 and 13), regardless of the size or position of the plate on the bed. If a type-high plate is 60 being registered, a marking part or blade 57 having a beveled edge 58, see Fig. 17, corresponding in height to the height of the beveled edge 59 (Fig. 8) of the type-high plate is employed in place of the marking part 43.

65 A frame 61 is movable with relation to the

bed, and is arranged to be placed in definite relation with the bed for coaction with the plate on the bed in the registering operation (Figs. 1, 2, 8 and 9). The frame is shown pivoted to the bed and is provided with a sheet 62 (Figs. 1 and 6), which is preferably a transparent sheet, being, for instance, of celluloid or other material through which the printing lines on the printing plate may be viewed when the sheet is in coactive relation therewith.

70 Means are also preferably provided for definitely locating the sheet with relation to the frame, which means are also preferably so arranged that the sheet may be removed and replaced for rearranging the sheet in previously determined definite relation with the frame for repeated use.

75 In the present exemplification the frame is a composite frame and is pivoted to the bed, the parts of the frame being pivoted to each other and serving as a clamp for clamping the transparent sheet in place. Thus 65 is exemplified as a main frame-member, provided with pivot-lugs 66, 67, at opposite corners thereof (Figs. 1, 2, 3, 4, 6 and 7). Pivot-supports 68, 69, are located at opposite corners of the bed and are shown adjustable with relation to the bed. The pivot-support 68 is provided with a pivot-pin 70 supported in bearings 71, 72, in a bracket 73 on the support. The pivot-pin is urged toward a pivot-recess 74 in the pivot-lug 66 by means of a spring 75 (see Fig. 4). The spring is shown as a spiral spring received about the pivot-pin between the bearing 71 and a collar 76 on the pivot-pin. The collar is preferably spaced from the bearing 72 by a space 77 for receiving the end of a screw-driver or other implement whereby the pivot-pin is urged outwardly for releasing the frame 61.

80 The pivot-support 69 is provided with a pivot-pin 81 received in a pivot-recess 82 on the pivot-lug 67 on the pivoted frame (Figs. 2 and 8). The pivot-ends of the pivot-pins 70, 81, are preferably conical, the pivot recesses 74, 82, being of complementary form for truly centering the pivot-frame on its pivots.

85 A supplemental frame-member 85 is pivoted to the main frame-member 65, as by means of pivot-pins 86, 87, located in complementary pivot-bearings at opposite corners of the frames, the pivot-bearings being respectively in the pivot-lugs 66, 67, on the main frame-member and in pivot-lugs 88, 89, on the supplemental frame member (Figs. 1 and 7).

90 The pivot-lugs 66, 67, on the main frame-member are provided with stop-pins 91 arranged to coact with stop-lugs 92 on the pivot-supports on the bed for positioning the pivoted frame 61 in rearwardly swung position (Figs. 2, 3, 4 and 7). The pivot-lugs on the supplemental frame are provided with stop-lugs 95 arranged to coact with stop-pins 96

extending inwardly from the pivot-lugs 66, 67, on the main frame-member (Fig. 7). The supplemental frame-member has a recess 97 (Fig. 4) at each of its pivoted corners for accommodating the pivot-lugs 66, 67, on the main frame-member.

The frame-members are shown as rectangular structures comprising marginal bars. The marginal bars of the main frame-member are at suitable intervals provided with locating pins 101 (Fig. 7). The sheet 62 (see Fig. 6) is provided with holes 102 corresponding distances apart for being received over the positioning pins and locating the sheet definitely with relation to the positioning frame. The supplemental frame-member serves as a clamp-frame, and is arranged to be received over the sheet and the positioning pins for definitely holding the sheet in stretched relation or flat with relation to the frame. The locating pins are received in recesses 103 in the supplemental frame. The sheet is in definite relation with the frame, the frame is in definite relation with the bed, and the printing plate is placed in definite relation with the bed.

The frame-members are preferably secured together with the transparent sheet between them, as by means of clamps 104 (Figs. 1, 11 and 12), shown as spring clips. Each of the clamps is pivoted to the upper frame-member on a pivot-pin 105, shown as a rivet, and is provided with a lip 106 arranged to be received under the lower frame-member for securely clamping the frame parts and the transparent sheets together. The clamps are provided with grips 107 for readily moving them.

Positioning means are provided for proper elevational position of the frame with relation to the bed so that the transparent sheet will be in proper relation with the plate when the frame is lowered. These positioning means are shown at the corners of the bed opposite the pivotal points of the frame, as stops 108 (Figs. 3, 8 and 9). Each of these stops has a shank 109 adjusted to elevation in a bore 110 in the bed, and secured in adjusted position by means of a set-screw 111. The frame is exemplified as arranged in Figs. 2 and 3 for locating the transparent sheet at proper height for registering an unmounted printing plate. My improved device is also arranged for registering printing plates which are type-high, for instance all-metal stereotype or electrotype plates or blocks, and printing plates mounted on or secured to wood or other bases. (See Fig. 8).

When marking such type-high plates, I prefer to correspondingly elevate the frame 61. The pivot-supports are preferably adjustable on the bed. Each of the pivot-supports is provided with a rib 112 received in a groove 113 in the bed (Figs. 7 and 8). A threaded stud 114 extends from the corner of

the bed and is received in a slot 115 in the pivot-support. A clamp-nut 116 is threaded over the stud and is provided with a hub 117 received in a complementary socket 118 in the pivot-support. This socket is at one end 70 of the slot 115. There is a similar socket 119 at the other end of the slot. When the hubs of the clamp-nuts 116 are located in the sockets 118 at the upper end of the slots at the respective pivoted corners of the frame 61, 75 the frame is pivoted for the height of unmounted printing plates. When the pivot-supports are elevated, and the hubs of the clamp-nuts 116 are located in the sockets 119, the frame 61 is elevated for proper height for 80 operating on type-high plates. When operating on type-high plates, the stops 108 for supporting the swinging end of the swinging frame 61 are elevated to corresponding heights by releasing the set-screws 111, raising the shanks 109 in their sockets 110 to proper heights, and again clamping said shanks by means of said set-screws in their new positions.

Instancing the operation of my improved 90 means in connection with registering unmounted printing plates intended for multi-color work, the printing plate 23 may be instanced as the key-plate for a set of printing plates, respectively arranged for printing 95 different colors imposed one on the other. The key-plate is provided with printing portions or printing lines, exemplified at 121, to depict the subject printed (Fig. 1). The various color plates are provided with printing 100 portions or printing lines complementary to the printing portions or printing lines on the key-plate, or a portion thereof. The transparent sheet is provided with lines 122 coincident with the overall width and the overall 105 length of the key-plate, these lines being drawn accurately central with relation to the centering lines 39, 40, on the supporting portion of the bed (Fig. 9). The lines 122 are preferably scratched on or into the transparent sheet or otherwise preferably permanently formed thereon. They are shown as depicting a rectangle to correspond with the area of the key-plate. The lines define the 110 outline of the key-plate.

The key-plate is located on the bed so that its margins are coincident with the locating lines 122 on the transparent sheet, the pivot-frame being swung downwardly for locating the transparent sheet immediately above the key-plate. The key-plate is readily shifted on the supporting surface by manipulation of the hand-wheels 31 for moving the key-plate lengthwise or sidewise or shifting the same angularly to accurately position the key-plate 120 with relation to the marking 122. The pivot-frame is then raised, and the slide 41 of the marker (Fig. 5) is moved in its grooves for contacting the marking part 43 with the margins of the key-plate, and providing said 125 130

margins with centering marks 55, 56, in line with the centering lines 39, 40, respectively (Fig. 9). The key-plate may be repositioned on the bed at any time by causing its marks 55, 56, to register with the centering lines 39, 40, on the bed. The register marks on the key-plate are shown made on the bevel faces of the margins thereof.

The key-plate in this position is suitably 10 inked, as by means of a hand inking roller, and the pivoted frame swung downwardly, and an impression 125 (Fig. 1) of the key-plate is made on the under face of the transparent sheet in suitable manner, as by rolling 15 a hand impression roller over the transparent sheet. The printing lines of the key-plate are thus transferred to the transparent sheet.

The key-plate is then removed from the 20 bed, and one of the color plates placed on the bed, the pivoted frame is swung downwardly for locating the transparent sheet having the printing 125 of the key-plate thereon over the color plate. The color plate 25 is then shifted by operation of the hand-wheels 31 for locating the printing lines of the color plate in registry with the complementary printed lines of the impression of the key-plate on the transparent sheet, thus causing 30 registry between said color plate and said impression and co-registry between the printing plates. When this registry has been effected, the frame of the transparent sheet is raised, and the marking tool moved lengthwise in its slots for marking the respective 35 margins of the color plate, and providing said margins with corresponding marks 55, 56, coincident with the centering lines 39, 40, on the bed, these marks being coincident on the color 40 plate with the corresponding marks on the key-plate.

The other color plates of the set are correspondingly marked. In this manner all the 45 complementary color plates are provided with corresponding register marks. All these register marks are made coincident with the centering lines on the bed, regardless of the sizes or shapes of the respective plates, and the plates are then mounted, the mountings 50 being gaged solely by the positions of the complementary register marks 55, 56, insuring that when mounted, the printing lines on all the color plates will register with each other for producing printing in perfect registry. Similar steps are taken for causing 55 co-registry between printing plates other than color plates, as for instance, correspondingly registering the printing plates for various pages in a book or for other purposes 60 wherein registering of printing plates or objects is desired.

I provide register bases 130 complementary to the registered plates (Figs. 13 and 14). The register base is a base on which the printing plate is mounted for producing a type-

high printing structure. The register base is provided with centering lines 131, 132, which are perpendicular to each other, respectively extending crosswise and lengthwise of the base, and being preferably parallel respectively with the ends and sides of the base. The printing plate provided with the register marks 55, 56, is placed on this base, with its register marks in accurate registry with the register lines 131, 132, on the base.

The base is provided with plate-securing means, shown as register hooks 135. The register hooks respectively comprise a register jaw 136, coacting with the beveled margin of the printing plate, and pivoted on a block 137, slidable in grooves 138 in the base. The block is preferably propelled in the groove by means of worms 139, 140, fixed to a shaft 141, journaled in bearings 142, 143, in the block and having a bevel pinion 144 thereon. The worms 139, 140, mesh with a rack 145 in the bottom of the groove 138.

The bevel pinion 144 is meshed by a bevel pinion 146 provided with a journal-stem 147, rotatable in the register hook, and having a socket 148, preferably square in cross-section, arranged to receive a suitable tool for turning the bevel pinion 146.

The block is provided with side tongues 95 151 received in slots 152 in the side walls of the groove 138 (Figs. 14, 15 and 16). The construction and operation of the register hook may be such as is usual or desired.

The base is provided with grooves 155 at its respective margins (Figs. 13 and 14). The base is also provided with projections 156, shown formed by the bodies of the register hooks. The projections 156 and the grooves 155 are complementary, the one being arranged to be received in the other located on neighboring bases for definitely positioning neighboring bases with relation to each other and locating neighboring bases so that their center lines 131, 132, align with each other, thus causing registry between plates on neighboring blocks, and causing registry between the printing lines on the various plates in a complete form, regardless of the number of plates that may be secured in the form. The normally projecting portions of these bodies are preferably devoid of the tongues 151, although the grooves 155 are provided with slots 157 (Fig. 15), complementary to the slots 152, for receiving the tongues 151 in extreme outward positions of the projections 156.

It is further desirable that certain of the bases be separated from each other different distances, for instance, to compensate for the folds between the superposed pages in a signature, the outer connected pages in the signature requiring larger margins between them than the inner connected pages of the signature. For this purpose I provide spac-

ing shims 161 (Fig. 15). These spacing shims may be of different thicknesses according to the number of pages and the relations of the pages in the form. The shims are provided with recesses 162 to accommodate the projections 156, so that these projections may connect adjacent plates across the shims.

When registering type-high plates, the frame for the transparent sheet is elevated, and the transparent sheet is provided with similar marginal lines similar to and coincident with the registering lines 122. The type-high plates include a key-plate and color plates, which are registered and marked similarly to the registering and marking of the key-plate and color plates hereinbefore mentioned. When such type-high plates are secured in the form, they are secured with the register marks of adjacent plates in registry with each other, so that all the plates of the form are in co-registry, as explained in connection with the printing plates hereinbefore described.

My improved means are simple for accomplishing the purposes intended. They further provide means whereby the registering marks may be so placed on the printing plates as not to mar or appear on the printed page; and, further, provide registering marks on the printing plate capable of being accurately placed in registry with registering marks on the base, and neighboring printing plates may be further co-registered, and the various bases in the printing form connected for definite and accurate registry throughout.

Having thus fully described my invention, what I claim as new, and desire to secure by Letters Patent, is:

1. In a printing plate registering device, the combination of a bed, a frame having connection therewith, a transparent sheet having marked thereon the outline of a key printing plate, means for releasably securing said transparent sheet in registered position on said frame, means on said bed for positioning said key-plate on said bed with its outline in registry with said outline mark on said transparent sheet, said bed provided with register marks, an edge marker for said key-plate for marking the edge of said key-plate in registry with said register marks on said bed, and guiding means on said bed for said marker for guiding said marker complementary to said register marks on said bed, said key-plate arranged to be printed on said transparent sheet, said positioning means on said bed permitting other printing plates respectively provided with printing portions whose printing lines are complementary to printing lines of said impression on said transparent sheet to be positioned on said bed with said printing lines on said other printing plates in registry with printing lines of said printed impression on said transparent sheet, and said edge marker arranged

to complementally mark the edges of said other printing plates while in such registered positions on said bed.

2. In a printing plate registering means, the combination of a bed, a frame pivoted to said bed, a transparent sheet, means on said frame for releasably securing said transparent sheet to said frame in position for receiving a printed impression on said transparent sheet from a printing plate positioned on said bed, said bed provided with register lines perpendicular to each other, means whereby to position complementary printing plates on said bed whereby to register printing lines on said respective complementary printing plates with printing lines of said impression on said transparent sheet, edge marking means, and guiding means between said bed and said edge marking means parallel with said respective register lines whereby to guide said edge marking means to complementally mark said printing plates so positioned on said bed in similar definite relations.

3. In a printing plate registering means, the combination of a bed, a frame comprising a pair of frame-members, means pivoting said frame to said bed, means pivoting said frame-members together, a transparent sheet, means releasably securing said transparent sheet between said frame-members, said bed provided with register lines perpendicular to each other, said transparent sheet provided with an outline-mark defining the outline of a printing plate, said transparent sheet having an impression thereon of said plate, edge-marking means for printing plates, and guiding means on said bed guiding said edge-marking means parallel with said respective perpendicular register lines and arranged for edge-marking printing plates complementary to said register lines.

4. In a printing plate registering means, the combination of a bed, a frame, a transparent sheet, means releasably securing said transparent sheet to said frame, said bed provided with register lines perpendicular to each other, said transparent sheet provided with an outline-mark defining the outline of a printing plate, said transparent sheet having an impression thereon of said plate, edge marking means for printing plates, guiding means on said bed guiding said edge marking means parallel with said respective perpendicular register lines and arranged for edge-marking printing plates complementary to said register lines, and means whereby the distance between said bed and said frame may be adjusted for accommodating unmounted and mounted printing plates between said bed and said transparent sheet.

5. In a printing plate registering means, the combination of a bed provided with registering marks, guiding means thereon complementary to said registering marks, a trans-

parent sheet, means for supporting said transparent sheet in predetermined relation with said bed for receiving a printed impression of the printing lines of a printing plate positioned on said bed, adjusting means on said bed for adjusting printing plates to position the printing lines thereon in registry with said printed impression, and marking means on said bed complementary to said first named 10 registering marks guided by said guiding means for marking said printing plates complementary to said first-named registering marks.

In testimony whereof, I have hereunto
15 signed my name.
